TIME SIGNAL SELECTOR SWITCH

Clare G. Judd, Highland Park, Mich.

Application October 21, 1946, Serial No. 704,668

19 Claims. (Cl. 200—37)

1

The invention relates in general to time control apparatus and more particularly to a device for automatically transmitting a signal to an apparatus, instrument or machine at predetermined time intervals.

An essential object of this invention is to provide a time control mechanism for closing any desired one of several circuits at predetermined periods. Such circuits may operate mechanism used for giving signals at various locations at predetermined times, may be used in connection with radios to turn a set on, select stations and/or turn a radio off at any desired period of time, or may be used with any other device wherein it is desirable to periodically receive an electrical signal.

A further object is to provide a simple and economical structure for effecting these functions.

A feature of this invention is to provide a switch device for controlling an electrical circuit having in combination a motor having a plurality of driving shafts, an element movable with one of the shafts and having a plurality of electrical contactors, a body having a plurality of electrical contactors and a member movable with a second shaft of different speed, and having a circuit closing conductor adapted to periodically electrically connect single contactors on each the element and body respectively.

Another feature of the invention is to provide a switch device having in combination a clock including hour and minute mechanism, a disc movable with the minute mechanism having a plurality of electrical contactors, a shell having a plurality of electrical contactors, an annular ring movable with the hour mechanism and having a single circuit closing conductor adapted to periodically electrically connect single contactors on each the disc and shell respectively, a plurality of distribution rings carried by the shell, and separate means on each of the contactors of the shell for selectively contacting one of the distribution rings.

Another feature is to provide a means for altering the relationship of the movable members to the stationary shell, thereby altering the period of contact between the contactors and the circuit closing conductor.

The foregoing, as well as other objects, will be more apparent as this description proceeds, especially when considered in connection with the accompanying drawings, wherein:

Figure 1 is a perspective view of the time signal selector embodying the features of the present invention;

2

Figure 2 is a sectional view taken substantially on the plane indicated by the line 2—2 of Figure 1;

Figure 3 is a sectional view taken substantially on the plane indicated by the line 3—3 of Figure 2;

Figure 4 is a sectional view taken substantially on the plane indicated by the line 4—4 of Figure 2; and

Figure 5 is a side elevational view of the time signal selector with portions broken away for clarity; and

Figure 6 is a sectional view taken on the line 6—6 of Figure 1.

15 In the several figures of the drawing the numeral 10 indicates the time signal selector having a body 11 including a casing or shell 12 and an inner housing 13. The casing 12 comprises a base portion 14 for mounting the selector 10, an upwardly extending cylindrical portion 15 and a cover or crystal 16. The cylindrical portion 15 is provided on its upper surface 17 with circumferentially spaced hour indicia 18 which may be painted, etched, printed or otherwise produced thereon so as to indicate the hour of day. A plurality of electrical contactors 19, herein shown as equal to 48 in number, are imbedded in the inner surface of the cylindrical portion 15, as shown in Figure 2, and have a relatively narrow 20 horizontal edge portion 20 exposed to the interior of the cylindrical portion 15. These contactors 19 are preferably molded integral with the casing 12 but, if desired, may be inserted in any suitable manner. Each of the contactors 19 are provided 25 with an extending strip 21 which is preferably twisted, as at 22, to provide a maximum bearing surface 23 for electrical contact, to be described later. The strips 21 are also molded integral with the casing 12, or otherwise secured thereto, and 30 each has its bearing surface 23 substantially flush with the inner surface 24 of the cylindrical portion 15 of the casing 12. Slots 25 are provided in the cylindrical portion 15 adjacent each extending strip 21 of the contactors 19.

45 The inner housing 13, comprising a tubular wall 26, an annular flange portion 27 at the top of the tubular wall 26, and a bottom flange portion 28, is screwed or otherwise secured within the casing 12, such as by screws 29 engaging a clamping ring 295 which bears against the bottom 28, and is provided on its outer surface 30 with a plurality of longitudinally spaced conducting rings or distributors 31 adjacent the slots 50 25 in the casing 12. The flange 27 is adapted to

receive screws 32 for securing the motor or clock mechanism 33 thereto.

The contactors 19 are constructed of a conducting material such as copper, brass or aluminum, and the casing 12 and inner housing 13 are preferably made of an insulating material such as plastic or wood. However, the casing 12 and inner housing 13 may obviously be constructed of a conducting material such as metal when provision is made for insulation of the same from the contactors 19.

Separate movable selectors 34 are provided to electrically connect each contactor 19 with any one of the rings 31, including a tab or handle 35 extending outwardly through the slots 25 and a spanner 36 between the casing 12 and inner housing 13. The spanners are provided with curled portions 37 and 38 on respective ends thereof adapted to electrically contact the strips 21 and the conducting rings 31 respectively, and to provide sufficient resilience to remain in any selected position. It will be noted that the rings 31 are inset or concave slightly to insure a positive connection with the adjacent curled portion 38 of the selector 34. The spanner may be constructed of any conducting material such as copper, brass or aluminum, and should preferably be of a resilient material.

In operation, it will be seen that by moving any one of the tabs 35 and therefore the spanners 36, it is possible to electrically connect any of the strips 21 and contactors 19 with any one of the rings 31 on the inner housing 13.

The element or disc 39 comprises an insulating body portion 40 and a plurality of electrical contactors 41, herein shown as equal to 43 in number, spaced from the axis of rotation of the disc 39 and imbedded in the periphery thereof. The contactors 41 have a relatively narrow edge portion 42 in vertical alignment with the contactors 19 on the casing 12. A conducting plate 43 is provided in the insulating body 40, in electrical contact with the contactors 41, having a recessed center portion 44 journaled with the minute mechanism of the clock 33. The plate is preferably molded integral with the insulating body 40, but may be inserted in any desired manner. The disc 39 is secured to the shaft or minute mechanism by means of a screw 45 or any other suitable means. A minute hand 46 is provided on the upper surface of the disc 39 for indicating the position thereof in relation to the indica 18 on the casing 12.

An annular ring 47 is rotatably supported between the disc 39 and the casing 12, and includes a ring portion 48 preferably of insulating material, and a plate 49 suitably connected to the shaft or hour mechanism of the motor or clock 33. A single circuit closing conductor 50 is provided in the annular ring 47 in vertical alignment with the contactors on the casing 12 and the disc 39 respectively. The plate 49, if of conducting material, is insulated from the circuit closing conductor as shown, as by molding the plate integral with the ring 48 in spaced relation to the circuit closing conductor 50. An hour indicating member 51 is provided on the annular ring 47 above the circuit closing conductor 50 for indicating the position of the annular ring relative to the hour indica 18. Member 51 may be raised as indicated in Figure 2, if hand 46 is elevated to clear it, or it may be merely a suitable indica on ring 47.

In operation, it will be seen that the annular ring 47, moving with the hour mechanism of the clock, will contact all 48 contactors on the

casing 12 each twelve hour period, or will be in contact with one of the contactors on the casing 12 once every fifteen minutes. The disc 39 revolving with the minute mechanism, will have each of its contactors 41 opposite each of the 48 contactors on the casing 12 once in each one hour period, or twelve alignments of the respective 48 contactors each fifteen minute period. However, due to the width of the contactors on the casing 12, and of the circuit closing conductor 50 on the annular ring 47 and the relative movement thereof, alignment of the conductors 19, 50 and 41 will be maintained only long enough for assurance of completion of the function of the accessory bells, lights, relays or such other devices as may be used to perform the end result desired. Moreover, the time period of this single alignment can be increased or decreased by utilizing either the complete or incomplete period of contact of a disc contactor 41, while one contactor 19 in the casing 12 is synchronized with the conductor 50 in the annular ring 47. To accomplish this, a dowel 52 is positioned in the bottom 28 of the inner housing 13 extending into an enlarged opening 53 in the base portion 14 of the casing 12. The screws 29 engaging the clamping ring 29b are loosened and the opposing set screws 54 and 55 threaded in the base portion 14 and bearing against the dowel 52 are adjusted to shift the inner housing 13 in relation to the casing 12. Since all the moving parts are mounted on the inner casing 13, the relationship of the contacts 19 and 41 can be adjusted and altered to produce a varied length of signal, or accomplish accurate timing of the initial contact between the conductors 19, 50 and 41.

The plate portion 43 on the disc 39 is in electrical contact with the minute mechanism shaft 56 which is in turn grounded on the housing of the clock 33. Leads 57 are provided from each of the rings 31 and individually may be connected to any desired circuit to directly operate mechanism, lights, etc., or preferably, to operate a relay or solenoid which, in turn, controls a circuit. Moreover, leads 57 are also provided for the selector ground circuit on the clock housing as well as the clock circuit, should it be desired to employ an electric clock.

Due to the size of the contactors and the possibility of damage thereto, it is desirable to use a relatively low voltage for operation of the time signal selector. This may be accomplished by utilizing the conventional line voltage of 110 or 220 connected through a step-down transformer or any other suitable means such as by the use of one or more dry or wet cells. It has been found that particularly advantageous results may be obtained without arcing or other damage to the contactors by using approximately 6 volts.

Although vertically spaced distribution rings 31 have been shown, it is obvious that other means such as a radial distribution could be employed without departing from the invention. Moreover, any number of distribution rings may be used, depending on the specific conditions.

As shown in the drawings, 48 contactors are utilized on each the casing and the disc respectively. However, this number may be increased or decreased to give a corresponding increase or decrease of signals per unit time. For example, with the 48 contactors shown, a signal is produced each fifteen minute period, whereas with 24 contactors, a signal would be produced each thirty minute period, and with 12 contactors, the signals

would be one hour apart. Likewise, an increase in the number of contactors, such as from 48 to 96, would produce the signal each seven and one-half minutes. It should be noted that by merely reducing the number of contactors on the disc, the time signal is similarly reduced. Moreover, the contactors on the casing may have irregular spacing, such as combinations of fifteen minute and one hour timing, described above, to obtain more rapid or slower rates of signalling at any 10 period of the day.

Twenty-four hour operation, or greater, may be accomplished by using a twenty-four hour clock mechanism and correspondingly arranging the contactors for the desired time interval. 15 Moreover, it is possible to employ a conventional twelve hour clock and still obtain twenty-four hour operation by doubling the number of distribution rings and employing a trip switch in the clock mechanism to utilize half of the rings for one twelve hour period and the other half for the other twelve hour period.

Ordinarily it is desirable to use a single circuit closing conductor in the annular ring operating with the hour mechanism. However, should it be desirable to receive a series of signals, such as three signals five minutes apart to the same distribution ring, this could be done by having three circuit closing conductors within a space less than the contactor spacing on the casing. Multiple signals to the same distribution ring could also be accomplished by increasing the width of the contactors on the casing or the width of the circuit closing conductor so as to allow a longer contact between the circuit closing conductor and the casing contactors and, therefore, permit two or more contactors on the disc to contact each time the contacts on the casing and annular ring align.

Only one selector or switch is shown in each slot in the drawings. However, it is obvious that if desired a plurality of switches, such as plug-in or bayonet type switches, may be employed to distribute the signal to a number of distribution rings.

What I claim as my invention is:

1. In a time controlled switch device for an electrical circuit, the combination of a pair of shafts, means for rotating the shafts at different rates of speed, a disc movable with one of the shafts and having a plurality of electrical contactors spaced circumferentially around its periphery, a stationary shell having a plurality of circumferentially spaced electrical contactors, and an annular ring movable with the other shaft and located between the contactors on the disc and shell respectively and having a circuit closing conductor adapted to connect progressively with specific single contactors on each said disc and said shell respectively.

2. In a time controlled switch device for an electrical circuit, the combination of a clock including hour and minute mechanism, a disc movable with the minute mechanism and having a plurality of electrical contactors around its periphery, a stationary shell having a plurality of electrical contactors, and an annular ring movable with said hour mechanism and located between the contactors on said disc and shell respectively and having a circuit closing conductor adapted to periodically electrically connect single contactors on each said disc and said shell respectively.

3. In a switch device for an electrical circuit,

the combination of a clock including hour and minute mechanism, an element movable with the minute mechanism and having a plurality of electrical contactors, a stationary body having a plurality of electrical contactors, a member movable with said hour mechanism and having a circuit closing conductor adapted to periodically electrically connect single contactors on each said element and said body respectively, and means for varying the length of contact between the contactors of said element and body respectively and the conductor on said member.

4. A switch comprising a stationary housing, a first set of circumferentially spaced contacts carried thereby in a circular array, a clock including hour and minute mechanism in said housing, a second set of circumferentially spaced contacts disposed in a circular array and driven by said minute mechanism in spaced concentric relationship to said first set of contacts, a bridging conductor driven by said hour mechanism intermediate said first and second set of contacts in concentric relation thereto and adapted to interconnect single ones of said first set of contacts with single ones of said second set of contacts in a patterned sequence.

5. In a time controlled switch device for an electrical circuit, the combination of a clock, including hour and minute mechanism; an element movable with the minute mechanism and having a plurality of electrical contacts about its outer circumference; a stationary body having a plurality of electrical contacts about its inner circumference; and a member movable with the said hour mechanism embodying a circuit closing conductor interposed between the contacts on said stationary body and the contacts on said moving element and adapted to contact progressively with single coincident contacts on each of the 40 said element and body respectively.

6. In a time controlled switch device for an electrical circuit, the combination of a clock, including hour and minute mechanism; a rotatable element movable with the minute mechanism and having a plurality of electrical contacts spaced about its axis of rotation; a stationary body having a plurality of electrical contacts in the same plane with those of the rotatable minute element; and a circuit closing conductor 45 interposed between the contacts on the stationary body and the contacts on the rotatable minute element and adapted to contact progressively with single radially coincident contacts on each of the said element and body respectively.

7. In a time controlled switch device for an electrical circuit, the combination of a pair of shafts; a clock for rotating the shafts at different rates of speed; an element movable with one of the shafts and having a plurality of electrical contacts radiating from its axis of rotation; a stationary body having a plurality of electrical contactors in plane with the contactors radiating from the moving element; a member movable with the other shaft and having a circuit closing conductor adapted to contact progressively with a pair of coincident contacts on the said body and element respectively; a clock support in said body, a plurality of concentric parallel annular rings around the clock support; and a separate 60 adjustable conductor member engaging each contactor on the said body and adjustable to connect with the desired distributor ring for selectively distributing the electric current from a supply source through the contacts of the movable element, the closing conductor and the contactors

on said stationary body to the desired electrical-
ly operated mechanism.

8. In a time controlled switch device for an electrical circuit, the combination of a pair of shafts; means for rotating the shafts at different rates of speed; an element movable with one of the shafts and having a plurality of electrical contactors; a stationary body having a plurality of electrical contactors; a member movable with the other shaft and having a circuit closing conductor adapted to contact progressively with specific single contactors on each said element and said body respectively; a plurality of distributors and separate adjustable means for selectively electrically connecting each contactor on said body with one of said distributors.

9. In a time controlled switch device, the combination of a clock, including hour and minute mechanism, mounted in a suitable support; an element movable with the minute mechanism and having a plurality of electrical contacts radiating from its axis of rotation; a stationary body concentrically surrounding the clock support and having a plurality of electrical contacts in plane with those on the movable element of the minute mechanism; a member movable with the said hour mechanism interposed between the said body and minute mechanism, and having an electric contact thereon adapted to bridge coincident pairs of contacts on said body and said element; a plurality of parallel distributor rings spaced along the outside of the clock support and concentric with the center of rotation of the shafts of the minute and hour mechanism; and a plurality of adjustable connectors adaptable to selectively connect the electrical contacts of the body to any desired distributor ring.

10. In a switch device, the combination of a clock including hour and minute mechanism; an element movable with the minute mechanism and having a plurality of electrical contactors; a stationary body having a plurality of electrical contactors; a member movable with said hour mechanism and having a circuit closing conductor adapted to periodically electrically connect single contactors on each said element and said body respectively; a plurality of distributors and separate adjustable means for selectively electrically connecting each contactor on said body with one of said distributors.

11. In a switch device for an electrical circuit, the combination of a clock including hour and minute mechanism; an element movable with the minute mechanism and having a plurality of electrical contactors; a stationary body having a plurality of electrical contactors; a member movable with said hour mechanism and having a circuit closing conductor adapted to periodically electrically connect single contactors on each said element and said body respectively; a clock support concentrically located within said body; a plurality of spaced rings about said clock support and adjustable means for selectively electrically connecting each contactor on said body with one of said rings.

12. In a switch device for an electrical circuit, the combination of a clock including hour and minute mechanism; a stationary body having a plurality of electrical contactors; a housing in said body for supporting the clock; an element movable with the minute mechanism of the clock and having a plurality of electrical contactors; a member movable with said hour mechanism and having a circuit closing conductor, the contactors on said body and element and said conductor

being mounted for concentric relative movement and positioned in relative wiping relation such that said conductor is adapted to periodically electrically connect single contactors on each said element and said body respectively, and means for adjusting said housing relative to said body.

13. In a switch device for an electrical circuit, the combination of a pair of shafts; means for rotating the shafts as different rates of speed; an element movable with one of the shafts and having a plurality of electrical contactors; a stationary body having a plurality of electrical contactors; a member movable with the other shaft having a circuit closing conductor adapted to periodically electrically connect single contactors on each said element and said body respectively; and means for varying the period of connection between the contactors of said element and said body respectively and the conductor on said member.

14. In a time controlled switch, a stationary body having a set of spaced contacts arranged in a circular array; a pair of shafts disposed concentrically with said contacts; means for rotating said shafts at different speeds; a set of spaced contacts driven by one of said shafts and movable in spaced relation to said first mentioned set of contacts; and a spanning conductor driven by said other shaft, movable between said sets of contacts and constructed and arranged to progressively connect single contacts of one set with single contacts of the other set.

15. A switch comprising a stationary housing; a first set of circumferentially spaced contacts carried thereby in a circular array; a clock including hour and minute mechanism in said housing; a second set of circumferentially spaced contacts disposed in a circular array and driven by said minute mechanism in spaced concentric relation to said first set of contacts; a bridging conductor driven by said hour mechanism intermediate said first and second set of contacts in concentric relation thereto and adapted to progressively connect single ones of said first of contacts to single contacts of said second set of contacts in a predetermined order in which connection to said first set is progressive from one to the next adjacent in continuous sequence, and to the second set is in predetermined, non-consecutive order.

16. A switch comprising a stationary support; a clock carried by said support, said clock having hour and minute mechanism; single coaxial circular series of circumferentially spaced contacts carried respectively by said support and said minute mechanism; a contact driven by said hour mechanism coaxially with said series of contacts and disposed to have wiping contact with both series to interconnect single contacts of one series with single contacts of the other series.

17. A switch comprising a stationary support; a clock carried by said support, said clock having hour and minute mechanism; single coaxial circular series of circumferentially spaced contacts carried respectively by said support and said minute mechanism; a contact driven by said hour mechanism coaxially with said series of contacts and disposed to have wiping contact with both series to interconnect single contacts of one series with single contacts of the other series; said clock being angularly adjustable with respect to said support to adjust the duration of dwell of the electrical connection through the contact driven by said hour mechanism with the simultaneously

coincident contact of each of said series of contacts.

18. In a time controlled switch device for an electric circuit, the combination of a clock including hour and minute mechanism; a stationary member having a plurality of electrical contacts disposed in a circular array; a first rotary member driven by said hour mechanism; a second rotary member driven by said minute mechanism; a plurality of electrical contacts carried by one of said rotary members and disposed in a circular array concentric with the contacts on said stationary member; an electrical contact on the other of said rotary members; said members being disposed such that a single contact on one of said members makes simultaneous contact with single contacts on said other two members so as to periodically establish electrical connection through different ones of the contacts on said stationary member.

19. Mechanism of the character described comprising a generally cylindrical shell having a plurality of electrical contacts therein disposed in a circular array; a conducting strip connected to each of said contacts and extending axially of said shell at its inner surface; a second cylindrical member in said shell having a plurality of annular electrical contact rings exposed in its outer surface; a plurality of circuit selecting

slides slidable axially in the space between the inner surface of said shell and the outer surface of said member, said slides each having a first contact portion continuously engageable with a strip of one of said contacts and a second contact portion engageable with a selected one of said rings; clock mechanism in said shell including hour and minute mechanisms; a circular series of contacts disposed concentrically with said first mentioned contacts and driven by one of said mechanisms, a contact driven by said other mechanism, said contacts being disposed in wiping relation such that electrical connections are completed sequentially from single contacts of said circular array through single contacts driven by said hour and minute mechanisms respectively.
